CLAIM

The ornamental design for a needle hub for a medical syringe, as shown and described.

DESCRIPTION

FIG. 1 is a front elevational view of a first embodiment of a needle hub for a medical syringe, in which the cylindrical base portion of the needle hub is provided with a spiral design that is lined for the color red;

FIG. 2 is a rear elevational view of the needle hub shown in FIG. 1;

FIG. 3 is a top elevational view of the needle hub shown in FIGS. 1 and 2;

FIG. 4 is a bottom elevational view of the needle hub shown in FIGS. 1-3;

FIG. 5 is a left side end view of the needle hub shown in FIGS. 1-4;

FIG. 6 is a right side end view of the needle hub shown in FIGS. 1-5;

FIG. 7 is a perspective view of the needle hub shown in FIGS. 1-6, with removable end caps shown exploded from the ends of the syringe carrying the needle hub;

FIG. 8 is a perspective view of a second embodiment of the needle hub shown in FIGS. 1-7, in which the cylindrical base portion of the needle hub is provided with a spiral design that is lined for the color black;

FIG. 9 is a perspective view of a third embodiment of the needle hub shown in FIGS. 1-7, in which the cylindrical base portion of the needle hub is provided with a spiral design that is lined for the color orange;

FIG. 10 is a perspective view of a fourth embodiment of the needle hub shown in FIGS. 1-7, in which the cylindrical base portion of the needle hub is provided with a spiral design that is lined for the color gray;

FIG. 11 is a perspective view of a fifth embodiment of the needle hub shown in FIGS. 1-7, in which the cylindrical base portion of the needle hub is provided with a spiral design that is lined for the color green;

FIG. 12 is a perspective view of a sixth embodiment of the needle hub shown in FIGS. 1-7, in which the cylindrical base portion of the needle hub is provided with a spiral design that is lined for the color purple;

FIG. 13 is a perspective view of a seventh embodiment of the needle hub shown in FIGS. 1-7, in which the cylindrical base portion of the needle hub is provided with a spiral design that is lined for the color pink;

FIG. 14 is a perspective view of an eighth embodiment of the needle hub shown in FIGS. 1-7, in which the cylindrical base portion of the needle hub is provided with a spiral design that is lined for the color blue;

FIG. 15 is a perspective view of a ninth embodiment of the needle hub shown in FIGS. 1-7, in which the cylindrical base portion of the needle hub is provided with a spiral design that is lined for the color yellow; and,

FIG. 16 is a perspective view of a tenth embodiment of the needle hub shown in FIGS. 1-7, in which the cylindrical base portion of the needle hub is provided with a spiral design that is lined for the color brown.

The broken line showing of the syringe illustrates the environment of the claimed design and forms no part thereof.

Those features of the alternate embodiments which are not shown in FIGS. 8-16 will be understood to be identical to those shown in the first embodiment of FIGS. 1-7.
